UNITED STATES PATENT OFFICE

WILLIAM MARCROFT, OF CRANSTON, RHODE ISLAND, ASSIGNOR TO UNIVERSAL WINDING COMPANY, OF BOSTON, MASSACHUSETTS, A CORPORATION OF MASSACHUSETTS

BUNCH-BUILDER FOR WINDING AND LIKE MACHINES

Application filed August 13, 1931. Serial No. 556,897.

This invention relates to improvements in bunch-builders for winding and like machines. It is particularly related to bunch-building devices of the type shown and described in U. S. Letters Patent No. 1,084,459, dated January 13, 1914, and No. 1,809,217, dated June 9, 1931.

A principal object of the present invention is to provide a device of the type specified which is capable of winding bunches of different yardages in accordance with the requirements of certain types of feeler-motions in looms.

Another object of the invention is to provide a device of the type specified which is capable of winding bunches and service windings on bobbins without appreciable variation in the tension of the yarn.

Another object of the invention is to provide a bunch-builder of the type specified which does not subject the yarn to undue strain and abrasion by contact thereon at a plurality of points.

Another object of the invention is to provide a bunch-builder of the type specified which is easier and more convenient to thread in preparing the winding machine for operation.

Another object of the invention is to provide a device of the type specified which is simple in construction and adapted for use with practically all types of winding machines without alteration in the arrangement of the mechanism thereof.

Further objects of the improvement are set forth in the following specification which describes a preferred embodiment of the invention, by way of example, as illustrated by the accompanying drawings. In the drawings:

Fig. 1 is a plan view showing the essential elements of a well known type of winding machine and illustrating the present improved bunch-builder as applied to use therewith;

Fig. 2 is a plan view corresponding to Fig. 1 and showing the present bunch-builder with its parts in position after the completion of the bunch and immediately prior to the transfer of the yarn to the thread-guide

which performs the service winding on the bobbin;

Fig. 3 is an end view of the winding mechanism showing the relation of the operating elements of the bunch-builder with respect thereto, with the yarn-controlling means illustrated in operative position by full lines and in transferring position by broken lines; and

Fig. 4 is a view showing the relative positions of the yarn-controlling means and thread-guide at the completion of the bunch winding and illustrating the method of transferring the yarn to the guide to effect the service winding.

In the prior patent first above referred to the bunch-building device is shown as comprising automatically-operated means adapted to engage and hold the yarn at the commencement of the winding of a cop or bobbin to limit its extent of traverse whereby to build a relatively narrow bunch on the bobbin or other yarn-receiver. Such means consists essentially of a swinging controller-arm having a notch or guideway through which the yarn draws as it leads to the bobbin to restrain it from being traversed by the thread-guide to any considerable extent, and automatically-operated means for swinging the controller-arm out of position after a predetermined interval to release the yarn to allow it to be traversed to the full extent by the guide to build the service winding on the bobbin.

In the second patent above referred to substantially the same mechanism is shown for releasing the yarn after the building of the bunch, but in lieu of the controller-arm initially held in fixed position to restrain the yarn from being traversed, a controlling-means or auxiliary guide is shown engaging the yarn and adapted to be reciprocated with the traversing thread-guide to impart a restricted traverse to the yarn during the building of the bunch. In this latter form of device the automatically-operated means acts to release the yarn from the auxiliary guide at the completion of the bunch whereby the yarn is thereafter traversed by the

thread-guide to the full extent during the service winding.

In the bunch-builder of each of these patents the yarn is engaged at two points during the building of the bunch, namely, by both the thread-guide and the controlling-means, the automatically-operated releasing means removing the controlling-means from the yarn to permit the service winding to be accomplished by the thread-guide alone. As a consequence of the yarn being engaged at two separate points, one of which is fixed and the other continuously reciprocated, in the case of the bunch-builder of the first-named patent the path of the strand is periodically altered in length with the result that the tension on the yarn is constantly varied. As a result of this action the yarn has a tendency to be wound rather loosely in the bunch during the movement of the thread-guide in one direction and much tighter upon the return movement of the guide. Such uneven winding is liable to cause a malformed or irregular bunch and the recurrent tightening of the strand increases the tension and strain on the yarn so that it is liable to become stretched and strained and sometimes broken. Moreover, in both instances where the yarn is engaged at two points during the bunch-winding it is subjected to excessive rubbing and abrasive action.

In the present improvement I make use of the automatically-operated mechanism of the prior devices to effect the release of the yarn after the building of the bunch, but in lieu of a controlling-means which restrains the yarn after its passage through the thread-guide to build the bunch, I employ means engaging the yarn to restrain it to build the bunch without requiring its passage through the thread-guide. In brief, the yarn-controlling means operates alone on the yarn to build the bunch and therafter the strand is transferred to the thread-guide which performs the service winding.

Referring first to Fig. 1 of the drawings, there is here illustrated a rotating winding-spindle 10 and reciprocating traverse-bar 11 of the same general arrangement as disclosed in the prior patents above referred to. The traverse-bar 11 is arranged opposite the spindle 10 and adapted to carry a pick-up yarn- or thread-guide 12 which is provided with a strand-guiding groove 13. Besides its reciprocating movement with the bar 11 the guide 12 is also fed progressively outward therewith to cause it to lay the yarn in superimposed conical layers advancing progressively along the spindle to build the cop or bobbin in the usual manner by longitudinal extension of the yarn mass. The winding-spindle 10 is journaled in bearings in a main frame 14 of the machine and is driven through suit-

able instrumentalities not herein shown or described.

A portion of the spindle 10 overhangs the front of the frame 14 and is adapted to mount a wooden bobbin B or other form of yarn-receiver. In some cases a paper tube may be used on the winding-spindle 10 in place of the wooden bobbin B as shown, or any other suitable form of yarn-receiver may be employed. The traverse-bar 11 is adapted to reciprocate in bearings in the frame 14, being actuated from a rocker-arm or other suitable mechanism, not herein shown or described. The bar 11 is preferably constructed in two parts, a main section 16 and a threaded section 17, connected at their adjacent ends by a pin and slot arrangement shown at 18. The outer end of the threaded section 17 of the traverse-bar 11 is mounted in a swiveled out-board-bearing 19, shown in Fig. 1, which allows its inner end to swing inwardly toward the winding-spindle 10.

The thread-guide 12 is supported at the end of an arm or guide-holder 21 which is hinged on the threaded section 17 of the bar 11. Engaging the threads of the section 17 of the bar 11 between the two legs of the thread-guide holder 21 is a nut 22, the turning movement of which feeds the guide 12 along the bar. A contact-wheel 23 carried on the nut 22 is adapted to engage the surface of the winding to advance the guide 12 with respect to the bobbin B. The swiveled arrangement of the threaded section 17 of the bar 11 allows the wheel 23 to be pressed in toward the winding-spindle 10 to adapt it to engage the first layers of yarn wound on the bare bobbin, and these elements operate in connection with a former-arm 24 of a type shown and described more particularly in Patent No. 1,809,217, previously referred to, to build the first layers of the bobbin.

The present improved bunch-building device is arranged in relation to the above-described mechanism as next explained. The improved construction herein shown includes an auxiliary guide or controller-arm 26 of substantially elbow-shape having its outer end forked to form a long finger 27, a shorter finger 28 and a notch or guideway 29 therebetween. The guideway 29 is adapted to receive the yarn y which is maintained therein in the position illustrated in Fig. 1 at the commencement of the winding operation for winding a bunch at the butt end of the bobbin.

With the devices of both of the prior patents above referred to the yarn is usually supplied to the winding-spindle from below, being guided through the reciprocating thread-guide before passing to the bunch-building means. In the present improved device, instead of passing the strand through the thread-guide before subjecting it to the control of the controller-arm, as shown in the prior art, and consequently causing it to be

reciprocated by the guide to no advantage while the bunch is being formed; the yarn passes downwardly from an overhead supply source or from an upper guide-bar, not shown, 5 and directly through the notch 29 of the controller-arm 26 to the bobbin. After the bunch is completed the controller-arm 26 is automatically thrown into the position illustrated in Fig. 2, and by broken lines in Fig. 3. By 10 this operation the yarn is transferred from the notch 29 of the controller-arm 26 to the groove 13 of the thread-guide 12 wherein it travels during the ensuing winding to build the main body of the bobbin in the conventional manner.

The mechanism for automatically throwing the controller-arm 26 is preferably of the type shown and described in the patents above referred to. The inner end of the controller-arm 26 is slotted as shown at 30 to adapt it to be adjustably secured by suitable screws 31—31 to a lever 32 of the operating mechanism. The automatic operating-mechanism may be contained in a casing 33 suitably attached to the frame 14 of the winding machine. The lever 32 is rockably mounted within the casing 33 and is formed with a right-angled toe or extension 37 carrying a pawl 34 adapted to check the rotation of a ratchet 35 controlled by a helical wind-up spring 36 coiled about its axis. The pawl 34 has a stop-finger 34' engaging the edge of the extension 37 of the arm 32 whereby under the movement of the latter in a clockwise direction the pawl will be released from the ratchet 35 to permit rearward rotation thereof for a purpose as later explained. Projecting radially from the ratchet 35 is a stop-finger 35' adapted to engage the end of the pawl 34 for the purpose of retaining the ratchet in initial position. An arm or lever 40 pivoted to the arm 32 at 41 carries a pawl 42 adapted to turn the ratchet 35 under the oscillating movement of the lever. The lever 40 is connected at 43 to the traverse-bar 11 to adapt it to be continuously oscillated therefrom. The pawls 34 and 42 are maintained in engagement with the teeth of the ratchet 35 by means of a spring 44 connecting their ends.

A cam 45 is mounted coaxially of and secured rotatively with the ratchet 35 and the end of the right-angled extension 37 of the lever 32 engages the periphery of the cam. 55 The cam 45 is cut away at one point on its periphery to form a concaved face 46 and a spring 47 connected to the lever 40 and anchored to the casing 33 tends to rock the arm 32 to urge its extension 37 against the cam. 60 The lever 32 being connected to the traverse-bar 11, each reciprocation of the latter causes the cam 45 to be rotated through the engagement of the pawl 42 with the successive teeth of the ratchet 35. The mechanism may be 65 adjusted to regulate the size of the bunch or

the length of yarn wound thereto by varying the position of the cam-face on the ratchet 35. When a bunch of the desired size or yardage has been wound the concaved face 46 of the cam will have been rotated into position to receive the right-angled extension 37 of the lever 32, whereupon the spring 47 will swing the lever 32 to move its extension 37 across the axis of the cam and the controller-arm 26 secured thereto will thus be carried 70 toward the thread-guide 12.

The method of operation of the complete device is as follows: Before starting the winding, the wooden bobbin B or other yarn-receiver is placed on the winding-spindle 10, 80 the yarn *y* led downwardly from its source of supply or overhead guide-bar and its end secured to the bobbin. The controller-arm 26 is next swung toward the traverse-bar 11 to the position illustrated by full lines in Figs. 1 and 3, and the yarn *y* placed in the notch 29 between the fingers 27 and 28. This adjustment of the controller-arm 26 swings the right-angled extension 37 of the arm 32 radially outward to engage its edge with the circular periphery of the cam 45 which is released to be rotated under the tension of the wind-up spring. It is noted that the adjustment of the arm 32 in the manner as above explained acts through the engagement of its extension 37 with the stop-finger 34' of the pawl 34 to release the latter from the ratchet 35. Upon the release of the ratchet the cam 45 is turned back until its stop 35' brings up 90 against the end of the pawl 34.

Threading of the yarn into the bunch-builder to prepare the machine for winding is extremely easy and convenient to accomplish, it being only necessary to engage the yarn in the notch 29 of the arm 26 without any further manipulation of the strand. The winding machine is started to rotate the winding-spindle 10 to wind the yarn onto the receiver B as it feeds thereto through the auxiliary guide or controller-arm 26. Concurrently with the rotation of the spindle 10 the traverse-bar 11 is reciprocated to cause the thread-guide 12 to traverse back and forth longitudinally of the bobbin B. Since as before explained, the strand or yarn *y* leads from above to the bobbin initially by way of the notch 29 in the end of the controller-arm 26 without being engaged by the thread-guide 12, the reciprocation of the latter does not affect the yarn. The yarn is therefore wound onto the receiver or bobbin B at the butt end thereof with only a short traversing movement as permitted by the width of the notch 29, thereby forming a narrow and compact bunch as indicated by the reference character *b*. 110

During the initial winding of the bunch on the bobbin B the controller-arm 26 remains fixed in the position shown in Fig. 1, its forked end extending across the spindle 115 120 125 130

- 10 toward the traverse-bar 11 and in a higher plane in order to maintain the yarn out of the path of the reciprocating thread-guide 12.
- 5 As the bunch winding proceeds the reciprocating movement of the traverse-bar 11 oscillates the lever 40 to actuate the pawl 42 to intermittently rotate the ratchet 35 and cam 45. After a predetermined number of oscillations 10 of the traverse-bar 11 the ratchet 35 will be sufficiently turned to bring the cut away portion 46 of the cam 45 into the position illustrated in Fig. 2 and at this point the lever 32 will be moved by the spring 47 to swing 15 the controller-arm 26 rearwardly to the position shown in broken lines in Fig. 3, thus moving the length of yarn guided thereby into the path of the thread-guide 12. This action is preferably timed to be rendered 20 simultaneously with the inward movement of the thread-guide 12 toward the position shown in full lines in Figs. 2, 3 and 4 or adjacent the butt end of the bobbin B. The retraction of the controller-arm 26 in the 25 manner explained causes the yarn y to slide from the recess 29 outwardly along the finger 27 to a point beyond the end of the shorter finger 28. Upon the next outward oscillation of the thread-guide 12 the yarn is picked 30 up thereby and drawn off from the end of the finger 27, thus being freed from the controller-arm 26 to be traversed by the thread-guide 12. It should be noted that the thread-guide 12 is of the pick-up or self-threading 35 type, having a curved finger 15 overlying its groove or threadway 13, see Fig. 4. As the guide moves to the left the yarn is engaged by the curved edge of the guide-holder 21 and directed against the side of the finger 15.
- 40 The continued movement of the guide in the direction indicated causes the yarn to slide along the finger 15 and pass under its end in the manner as illustrated by full lines in Fig. 4. The yarn is thus seated in the groove 13 45 of the guide 12 to be thereafter prevented from release by the finger 15 which acts as a guard therefor as shown by dash lines in Fig. 4. In this manner, when the bunch winding is completed the yarn is released from the 50 auxiliary guide 26 and transferred to the reciprocating thread-guide 12 to be laid on the bobbin with the full extent of traverse for the service winding. The machine will thereafter continue to operate to wind the 55 yarn with the full extent of traverse to build the service winding forming the main body of the bobbin which is constituted by a series of conical layers of yarn stepped progressively forward toward the tip end of the spindle 10.
- 60 When the bobbin is completed in the form as illustrated by dot-and-dash lines in Fig. 1 it is doffed from the spindle 10 and an empty receiver placed thereon. The controller-arm 26 is then manually rocked 65 against the tension of the spring 47 into the

position shown in Fig. 1, where it is once more held by the return of the cam 35 to first position as shown in Fig. 1. The winding of a new bobbin may then proceed as before in the manner as above explained.

In some cases it is desirable to change the location of the bunch with respect to the butt of the bobbin, that is, to wind it at a greater or a lesser distance therefrom. This is accomplished by simply loosening the screws 31 in the arm 32 and extending or shortening the length of the controller-arm 26 projecting therefrom so as to adjust the position of the notch 29 in relation to the end of the bobbin.

It will be observed from the foregoing that the present invention provides for a much easier and more convenient method of threading up the yarn in the winding machine to prepare the latter for operation. Where in other types of bunch-building devices it has been necessary to place the strand in the thread-guide before threading it into the controller for the bunch-winding means, in the present device the yarn is simply engaged with a single guiding means, that is, the notch in the controller-arm. As a further important advantage of this arrangement in the present device the yarn is not caused to make a plurality of sharp bends at different points of contact with its guiding means and thus is relieved of unnecessary strain and abrasive action.

While I have herein described and illustrated my improved bunch-building device as embodied in a preferred form of mechanism and applied to use in connection with a certain type of winding machine, it is to be understood that modifications may be made in the construction and arrangement of the device and in its adaptation to winding machines of other types without departing from the spirit or scope of the invention. Therefore, without limiting myself in this respect, I claim:

1. In a winding machine, the combination of means for traversing yarn on a receiver to wind a cop or bobbin, means for initially holding the yarn out of the path of the traversing-means to prevent it from being engaged therewith whereby to wind a bunch on the bobbin, and means for transferring the yarn from the holding means to the traversing-means upon the completion of the bunch winding.

2. In a winding machine, the combination of means for traversing yarn on a receiver to wind a cop or bobbin, means for guiding the yarn to the receiver in a course outside the path of the traversing-means to restrain it from engagement therewith during the winding of a bunch on the receiver, and means operative upon the completion of the bunch to shift said guiding-means into position to transfer the yarn therefrom to the traversing means.

3. In a winding machine, means for laying a service winding of yarn on a receiver, means for winding a bunch on the receiver by preventing the yarn from engagement with the 5 service winding means for a predetermined period, and means to transfer the yarn from said bunch-winding means to the service-winding means.
4. In a winding machine, means for laying 10 a service winding of yarn including a reciprocating guide for the yarn, means for winding a bunch by withholding the yarn from engagement with the guide at the start of the winding operation, and means for transferring 15 the yarn from the bunch-winding means to the reciprocating guide.
5. In a winding machine, the combination 20 of means for traversing yarn on a receiver to wind a cop or bobbin, means for guiding the yarn in a path to prevent it from being engaged with the traversing-means whereby to build a bunch, and means for transferring the yarn from the bunch-winding means to the traversing-means.
- 25 6. In a winding machine, the combination of means for laying a service winding of yarn on a receiver, means for building a bunch on the receiver before the service winding is commenced by withholding the yarn 30 from engagement with the service-winding means, and mechanically-actuated means operated upon the completion of the bunch to transfer the yarn from the bunch-winding means to the service-winding means.
- 35 7. In a winding machine, the combination of means for traversing yarn to a predetermined extent to form the service winding of a bobbin, means for withholding the yarn from engagement with the traversing-means 40 whereby to build a bunch, and means for transferring the yarn from the bunch-winding means to the traversing-means.
8. In a winding machine, the combination 45 of means for traversing yarn on a bobbin to lay a service winding, means for restraining the yarn to cause it to wind with a shorter traverse to build a bunch before the traversing means engages the yarn, and means actuated from the traversing-means upon the 50 completion of the bunch to shift the restraining means to transfer the yarn to the service-winding means.
9. In a machine of the type specified, the 55 combination of a rotating winding-spindle, a guide for traversing yarn to wind a bobbin on the spindle, an auxiliary guide for engaging the yarn to build a bunch before the first-mentioned guide engages the yarn, said auxiliary guide being initially positioned to restrain the yarn from engagement with the 60 traversing-means during the bunch winding, and means for transferring the yarn to the first mentioned guide after the completion of the bunch.
- 65 10. In a machine of the type specified, the combination of a rotating winding-spindle and a thread-guide for the yarn arranged to be reciprocated one with respect to the other, an auxiliary guide for engaging the 70 yarn to build a bunch before the first mentioned guide engages the yarn, said auxiliary guide being initially positioned to restrain the yarn from engagement with the thread-guide during the bunch winding, and means operative on the auxiliary guide to transfer the yarn therefrom to the thread-guide to build the body of the bobbin.
11. In a winding machine, the combination 75 of a winding-spindle and thread-guide adapted to be reciprocated one with respect to the other to traverse yarn to wind a bobbin, an auxiliary guide adapted to hold the yarn to prevent its engagement with the thread-guide at the beginning of the winding to build a bunch on the bobbin, and automatically-operated means for moving the auxiliary guide with respect to the winding-spindle to transfer the yarn therefrom to the thread-guide whereby it is traversed to the 80 full extent to wind the main portion of the 85 bobbin.
12. In a winding machine, the combination 90 of a winding-spindle, a thread-guide reciprocable longitudinally of the spindle to wind a bobbin thereon, a controller-arm adapted to hold the yarn to prevent its engagement with the thread-guide as it leads to the bobbin whereby to wind a bunch, and means for moving the controller-arm toward the thread-guide to transfer the yarn thereto 95 to wind the body of the bobbin.
13. In a winding machine, the combination 100 of a winding-spindle, a thread-guide reciprocable longitudinally of the spindle to wind a bobbin thereon, a pivoted controller-arm for holding the yarn to prevent its engagement with the thread-guide to wind a bunch, and means for swinging the controller-arm to transfer the yarn to the thread-guide to 105 wind the body of the bobbin.
14. In a winding machine, the combination 110 of a winding-spindle, a thread-guide reciprocable longitudinally of the spindle to wind a bobbin thereon, a controller-arm for holding the yarn to prevent it from engagement with the thread-guide whereby to wind a bunch, and ratchet-controlled means for moving the arm toward the thread-guide to transfer the yarn thereto to wind the body 115 of the bobbin.
15. In a yarn winding machine, a guide for the yarn, means for traversing the guide in a predetermined path, a pivoted arm adapted when in one position to engage the 120 yarn to withhold it from the path of the guide to prevent its engagement therewith and when in another position to locate the yarn in the path of the guide, and means for moving the arm.
16. In a winding machine, a rotating spin- 125

- dle, a thread-guide, means for traversing the thread-guide with respect to the spindle to wind a cop or bobbin thereon, a pivoted arm for controlling the yarn to wind a bunch,
5 means for holding the arm in fixed position to withhold the yarn from engagement with the thread-guide to build a bunch, and means for moving the arm to transfer the yarn to the thread-guide.
- 10 17. In a yarn winding machine, a traversing guide for the yarn adapted to pick up the strand upon contact therewith, means for traversing the guide in a predetermined path, a controller-arm adapted when in one position to withhold the yarn from the path of the guide to prevent its engagement therewith and in another position to locate the yarn in the path of the guide whereby the latter will pick up the yarn, and means for moving the arm to transfer the yarn therefrom to the guide.

In testimony whereof I hereunto affix my signature.

WILLIAM MARCROFT.
